UNITED STATES PATENT OFFICE

156,047

DESIGN FOR A SLIPPER OR SIMILAR ARTICLE

Henriette Simon, New York, N. Y.

Application November 12, 1948, Serial No. 149,600

Term of patent 3½ years

(Cl. D7—7)

To all whom it may concern:

Be it known that I, Henriette Simon, a citizen of the United States, residing at New York, in the county of New York and State of New York, have invented a new, original, and ornamental Design for a Slipper or Similar Article, of which the following is a specification, reference being had to the accompanying drawing, forming part thereof.

In the drawing:

Fig. 1 is a side view, in perspective, of a slipper showing my new design;

Fig. 2 is a rear view thereof, in perspective, and

Fig. 3 is an enlarged top view, in perspective.

I claim:
The ornamental design for a slipper or similar article, substantially as shown.

HENRIETTE SIMON.
